DESIGN FOR A DISPLAY BOX

Lloyd P. Lazenby, Atlanta, James A. Reeves, Hapeville, and William Tucker Wayne, Atlanta, Ga., assignors to Scripto Manufacturing Company, Atlanta, Ga., a corporation of Georgia

Application November 1, 1943, Serial No. 111,564

Term of patent 14 years

To all whom it may concern:

Be it known that we, William Tucker Wayne, Lloyd Preston Lazenby, and James Albert Reeves, citizens of the United States, residing at Atlanta, Atlanta, and Hapeville, respectively, in the county of Fulton and State of Georgia, have invented a new, original, and ornamental Design for a Display Box, of which the following is a specification, reference being had to the accompanying drawing, forming part thereof.

The figure is a perspective view of a display box, showing our new design.

The lining of the central circle and of the scroll denotes red; and the panel portion is shaded to indicate contrasting colors.

The rear of the box is plain and unornamented, and the opposite end of the display box is similar to the end illustrated.

We claim:

The ornamental design for a display box, as shown and described.
